HAND ABRADING TOOL

Alfred E. Anheuser, Milwaukee, Wis.

Application September 28, 1953, Serial No. 26,979

Term of patent 14 years

(Cl. D37—1)

To all whom it may concern:

Be it known that I, Alfred E. Anheuser, a citizen of the United States of America and residing at Milwaukee, in the county of Milwaukee and State of Wisconsin, have invented a new, original, and ornamental Design for Hand Abrading Tool, of which the following is a specification, reference being had to the accompanying drawing, forming a part thereof, and in which

Figure 1 is a perspective view of a hand abrading tool embodying my new design;

Figure 2 is a plan view thereof; and

Figure 3 is a side elevational view thereof.

The dominant features of my design reside in those portions thereof illustrated in full lines.

I claim:

The ornamental design for a hand abrading tool, as shown and described.

ALFRED E. ANHEUSER.
